UNITED STATES PATENT OFFICE.

C. A. MCPHETRIDGE, OF ST. LOUIS, MISSOURI.

IMPROVED BINDER FOR GRAIN-HARVESTERS.

Specification forming part of Letters Patent No. 16,097, dated November 18, 1856; antedated October 25, 1856.

To all whom it may concern:

Be it known that I, C. A. MCPHETRIDGE, of the city and county of St. Louis, and State of Missouri, have invented a new and Improved Automatic Binder for Grain-Harvesters; and I do hereby declare that the following is a full and exact description thereof, reference being had to the accompanying drawings and to the letters of reference marked thereon.

The nature of my invention consists in the peculiar construction of an automatic binder for grain-harvesters.

To enable others skilled in the art to make and use my invention, I will proceed to describe its construction and operation.

Figure 1 is a plan view. Fig. 2 is a side elevation. Fig. 3 is a section of the binder, open to receive the grain. Fig. 4 is a section of the binder closed, and in the act of binding the sheaf. Fig. 5 is a section, showing the slotted cutting-plate. Fig. 6 is a section through the line $x-x$ in Fig. 4, showing the twister with its conical projections for catching and twisting the ends of the wire together.

In the construction of my invention, in Fig. 1, A is the wheels, and B the shaft or axle; C, the balance-wheel, and D the shaft; E, the seat; F, the platform; a, the pulleys for carrying the endless belts; b, the endless belts; c, the spring-separators; G, the spring-pliers on the upper end of the reciprocating arm G'; d, the friction-wheel; n, the loose pulley on shaft with wheel d; H, gear-wheel on axle B; L, the revolving knife; e, the cam for operating lever f, which operates the reciprocating arm G'; g, the lever for operating the wheel d, for operating the binder by means of it; h, a pin for operating the connecting-lever h', which operates the ejecting-rake i, which is for removing the sheaf when it is bound; j, the spring operating on the said rake, and restoring it to its position to be again caught in the sheaf when being bound; k, the spool to hold the coiled wire.

In Fig. 2, A is the driving-wheel; C, the balance-wheel; a, the pulleys for endless belts; c, the spring-separators; G, the spring-pliers; G', the reciprocating arm; f, lever for operating the reciprocating arm; e, the cam on shaft B for operating lever f; g, a lever for

operating the binder by means of friction-wheel d; E, the seat; h, a pin attached to shaft B; h', the connecting-lever; i, the ejecting-rake; k, the spool for the coiled wire; l, the wire; m', the shaft for revolving the twister; j, the spring for replacing the ejecting-lever; n, loose revolving pulley on the shaft m; o, movable plate on same shaft, with square bearings, and made to slide loosely on the shaft m'; p, wire-holder; q, slotted cutting-plate, and to guide the wire to the twister, and for cutting off the wire; q', the inclined friction-brake; r, the twister, which is made of a conical form, with projections or teeth for the wire to fall into, and for holding it until it is twisted; K', the frame for supporting the ejecting-rake; L, the revolving knife.

In Fig. 3, k is the spool containing the wire coil; M, the stationary arm; m', the shaft; n, loose pulley; o, movable plate; p, wire-holder; q, slotted cutting-plate, and to guide the wire to the twister; r, the twister; l, the wire; G, the spring-pliers on the end of the reciprocating arm G', for holding the wire.

In Fig. 4, K is the spool with wire coil on it; M, stationary arm; n, loose pulley; o, movable plate; m', shaft; p, wire-holder; q, the slotted cutting-plate; r, the twister; l, the wire; G, the spring-pliers; G', the reciprocating arm brought up and in the position of binding.

In Fig. 5, q is the slotted cutting-plate; S, the hole for the shaft m' to pass through; t, slot for the wire to pass into the twister; u, spring for pressing back the wire, which may be a straight spring, as at u, or a spiral spring, as at u'.

In Fig. 6, r is the pinion or twister; r', the projections for catching the wire; G, the spring-pliers; M, the stationary arm; a', the slot or opening in spring-pliers.

In the operation of the twister it may be briefly described as follows: When the spring-pliers G first come in contact with friction-brake q', the friction against pulley n on shaft m' is just sufficient to revolve the twister half round, or until the wire comes in contact with cutting-plate q, when it stops until spring-plier G has been forced fully up to its place, when the friction then becomes sufficient to revolve the twister, which now

catches the wire from the spring-pliers G, and quickly twists the ends together.

In operating the binder, I first wind the wire on spool K, thus forming a coil. I then pass it down through the wire-holder p, as seen in Figs. 2 and 3. It is then caught in the spring-pliers G, as seen in Fig. 3, and reaches across the space into which the grain is reeled by the endless belts b, as shown by the position of the wire l in Fig. 3. The weight of the grain falling on the wire causes it to assume the position shown in dotted lines 1 and 2, fitting itself to the stationary arm M.

The reciprocating arm is now caused to rise and approximate the twister, by means of the cam e and binding-lever f, until it comes in contact with friction-brake q', with inclined sides, and pushing the wire before it, by means of the sheaf, against the spring u into slot t, until it comes in contact with twister r, when it is caught by the twister, as shown by dotted lines 2 in Fig. 3. The movable plate o is now brought slightly in contact with loose revolving pulley n, driven by a belt and always in motion. The movable plate o, fitting on a square portion of the shaft m', causes the shaft to revolve with it, carrying the twister half round, until the wire is brought in contact with the cutting-plate q, as shown in dotted lines in Fig. 4.

The reciprocating arm is now pressed up by the lever f and cam e, and forcing the spring-pliers G against the inclined shoulders of the wire-holder, which opens slightly the spring-pliers to relieve the wire; but before the wire is relieved it is caught in the twister, around which the end of the spring-pliers fits

closely. The twister now revolves and cuts off the wire in contact with the cutting-plate q. The wires, being both caught in the twister on opposite sides, are twisted together until they pass down out of the twister into the sheaf.

The sheaf being now bound, it is ejected from the stationary arm by means of the ejecting-rake i, which is operated by means of the pin h and connecting-lever h'. As the reciprocating arm recedes, the spring-pliers catch the wires in the jaws, as before, the spring u having already thrown it back out of the slot where it was cut off by the twister and cutting-plate to its bearing-point in wire-holder p, ready to be caught by spring-pliers G.

The operation of binding now being completed, the reciprocating arm is thrown down by means of the spring-separators c, which rest on bar v, attached to the spring-pliers G, and is now ready for a second operation.

What I claim as new, and desire to secure by Letters Patent, is—

The combination of the reciprocating arm G', with spring-pliers G attached, with stationary arm M, revolving twister r, cutting-plate q, friction-brake q', spring u, and movable plate o, when the same are constructed and arranged to operate in relation to each other and the main frame and driving-wheel, for the purpose of binding grain from a continuous coil of wire, in the manner above described and set forth.

C. A. MCPHETRIDGE.
